UNITED STATES PATENT OFFICE.

JOHN CLEELAND, OF ST. LOUIS, MISSOURI.

CABLE-REEL TURNER.

No. 820,552.

Specification of Letters Patent.

Patented May 15, 1906.

Application filed January 8, 1906. Serial No. 295,203.

To all whom it may concern:

Be it known that I, JOHN CLEELAND, a citizen of the United States, residing at the city of St. Louis, State of Missouri, have invented 5 a certain new and useful Improvement in Cable-Reel Turners, of which the following is a specification.

My invention relates to a new and useful improvement in cable-reel turners, and has 10 for its object to provide a device for the purpose of turning cable-reels for winding and unwinding cable.

With these ends in view this invention consists in the details of construction and combination of elements, hereinafter set forth 15 and then specifically designated by the claim.

In order that those skilled in the art to which this invention appertains may understand 20 how to make and use the same, the construction and operation will now be described in detail, referring to the accompanying drawings, forming a part of this specification, in which—

25 Figure 1 is a side view of a cable-reel with the reel-turner in place. Fig. 2 is a top view of a cable-reel with the reel-turner in place. Fig. 3 is a side view of the angle-iron 8, with the socket-bolt 9, washer 10, and nut 11 in 30 position. Fig. 4 is a front view of the knuckle-hinged joint and angle-iron 8 in position. Fig. 5 is a sectional view of the angle-iron 8, showing the knuckle-hinged joint in position. Fig. 6 is an end view of the angle-iron 8, with 35 the socket-bolt 9, washer 10, and nut 11 in position.

1 is the cable-reel and does not relate to my invention.

2 is the cable and does not relate to my invention.

3 is the reel-bar on which the cable-reel is mounted.

4 is the screw-jack, on which the reel-bar is supported.

45 5 is the vertical rod and forms part of my invention.

6 represents the holes in the T-iron lever 7.

7 is the T-iron lever.

8 is the angle-iron, with teeth or notches in 50 both legs to prevent it slipping on the edges of the reel when the handle is lowered and which forms a part of my invention.

9 is the socket-bolt, in which the hooked end of the vertical rod 5 rests, forming the 55 knuckle-hinged joint, which forms a part of my invention.

10 is a washer which is filed out so as to fit snugly and firmly down on the angular surface of the angle-iron 8, as shown in Fig. 5.

11 is a nut which fits on the threaded end 60 of the socket-bolt 9.

12 is a bolt with a threaded end which holds the vertical rod 5 and the T-iron lever together.

13 is a rabbit-eared nut which screws onto 65 the threaded end of the bolt 12.

14 is the handle-bar.

When the cable-reel is mounted on the reel-bar 3, which in turn is mounted on the screw-jacks 4, the T-iron lever 7, which runs 70 horizontal with the reel-bar 3, is connected at points indicated by holes 6, as shown in Fig. 1, to the forked end of the vertical rod 5 on each side, as shown in Fig. 4, by the threaded bolt 12 and rabbit-eared nut 13, so that when 75 the handle-bar 14 is raised the vertical rod 5, though stationary with the T-iron lever, will not be rigid.

The other or upper end of the vertical rod 5 is hooked, as shown in Fig. 4, and is hooked 80 into and rests in the socket of the socket-bolt 9, forming a knuckle-hinged joint. On the socket-bolt 9 rests the angle-iron 8, which has teeth or notches in both legs and which is held firmly in place by the washer 10 and the 85 nut 11. When the handle-bar 14 is raised, the angle-iron 8 is allowed to tip over on its side, with the teeth or notches turned toward the handle-bar 14 by means of the knuckle-hinged joint, and the angle-iron moves 90 forward on the arc surface of the cable-reel 1 a proportionate distance as the handle-bar 14 is raised, as indicated by the dotted position of the T-iron lever 7 and vertical rod 5 in Fig. 1. Then as you lower the handle-bar 14 95 the angle-iron 8 is allowed to turn over, with the teeth down, thus taking hold on the edges of the cable-reel 1, thus forcing the reel to turn.

This device can be adjusted to fit different-size cable-reels by means of changing the vertical rod 5 to the different holes 6 shown in the T-iron lever 7.

One man can accomplish as much work 100 with the assistance of this reel-turner as four 105 men could without it.

Having thus described the invention, what I claim is—

The combination in a cable-reel turner, of a cable-reel and a T-iron lever, with a vertical 110 rod connected thereto stationary but not rigid, the other end of said vertical rod being

hooked, which is hooked into the socket of a socket-bolt, and a socket-bolt, together with an angle-iron, with teeth or notches in both legs, resting firmly or rigidly on said socket-bolt by means of a washer and nut screwed onto the threaded end of the socket-bolt, all substantially as set forth.

In testimony whereof I have hereunto affixed my signature in the presence of two subscribing witnesses.

JOHN CLEELAND.
